UNITED STATES PATENT OFFICE.

RALPH H. ROSENBERG, OF COLUMBUS, OHIO.

INTERNAL-COMBUSTION ENGINE.

1,182,587.

Specification of Letters Patent.

Patented May 9, 1916.

Application filed December 18, 1911. Serial No. 666,445.

To all whom it may concern:

Be it known that I, RALPH H. ROSENBERG, a citizen of the United States, and a resident of Columbus, Franklin county, Ohio, have invented certain new and useful Improvements in Internal-Combustion Engines, of which the following is a specification.

My invention relates to improvements in internal combustion engines and has particular reference to improvements in the valves and valve mechanisms of such engines.

The general objects of my invention are to increase the power, efficiency and fuel economy of internal combustion engines; decrease the wear incident to power production, or, in other words, increase the life of such engines; reduce and, as far as possible, eliminate the noise incident to operation; and to lessen the vibration of such engines when running.

A further object of my invention is to provide a main valve and associated parts of such ample dimensions that the necessary movements of the valve shall be accomplished easily and noiselessly.

A further object of my invention is to provide a multiple cylinder internal combustion engine, wherein the cylinders shall be so arranged and connected that the ingress and egress of the gases to and from the various cylinders shall be facilitated and wherein the flow of the fuel gas shall be equally free to all of the cylinders.

My invention consists in an internal combustion engine having the characteristics above outlined and having one or more power cylinders each provided with a combined inlet and outlet valve reciprocally mounted within the explosion space of the cylinder, circumferentially arranged inlet and exhaust ports entering said space and controlled by said valve, and mechanism operatively connecting the valve with the engine shaft.

My invention further consists in an internal combustion multiple cylinder engine having in each of its cylinders a reciprocating balance valve arranged within its explosion space adapted to control relatively long inlet and exhaust ports, and said engine having relatively large inlet and exhaust gas chambers common to and uniting all of the inlet and exhaust ports respectively.

My invention further consists in the various constructions and combinations of parts by means of which the above and other objects are attained, and all as hereinafter described and particularly pointed out in the appended claims.

In the accompanying drawings, which form a part of this specification: Figure 1 is a central, vertical, longitudinal section of a six-cylinder engine embodying my invention; Fig. 2 is a plan view of the engine; Fig. 3 is an enlarged, transverse, vertical section on the line 3—3 of Fig. 1; Fig. 4 is a side elevation of the engine, partly in central section and having a portion broken away to show the cams; Fig. 5 is a horizontal section through the common fuel gas supply chamber and inlet ports on the line 5—5 of Fig. 1; and Fig. 6 is a section similar to Fig. 5, but taken through the exhaust ports and common exhaust chamber on the line 6—6 of Fig. 1.

While I have chosen to illustrate my invention as applied to the construction of a six-cylinder engine adapted for use in automobiles, it should be understood that the invention is also applicable to single cylinder engines and other multiples designed for the same and other uses.

The development of the internal combustion engine for use in automobiles has shown the desirability of improvement along a number of lines. For instance, it is desirable that the ratio of the possible power development to the weight of the engine be increased; that the noise and vibration incident to the operation of the engine be eliminated to the greatest extent possible, and that the cost of construction be reduced as much as possible while maintaining the mechanical efficiency. These desirable ends are attained in engines embodying my invention, and in the following description of the engine illustrated the various advantageous features of my invention and the functions of the related parts and mechanisms will be made plain.

As illustrated in the drawings, I prefer to make the engine of two main castings, the upper one A containing the cylinders, and the lower one B forming the base and crank case, and the two parts are bolted together. The crank shaft 3 extends longitudinally through the crank case and is supported in suitable bearings 4, 5 and 6, the bearings 4 and 6 being arranged at the

ends of the engine and the bearing 5 at the middle. This arrangement of bearings divides the six crank pins of a six cylinder engine, as shown, into two groups of three each. The individual pins in each group of three are equally spaced around the crank circle, that is, these crank pins are spaced 120 degrees apart and consequently each group of three crank pins is thus perfectly balanced. I prefer to form the cranks projecting radially from the center line of the shaft in each instance, and this provides a shaft which is substantially evenly balanced between each two bearings, that is, the weight is evenly distributed circumferentially around the shaft and added counterbalanced weights are not required, which is not the case in shafts of this kind where adjacent crank pins are arranged at 20 degrees from each other, and wherein the bearings are spaced at other positions than between groups of three crank pins. The cylinders 7 are arranged vertically above the crank shaft parallel with one another and each thereof is closed at its upper end by an integrally formed head 8. The working portions of the cylinders and their heads are surrounded by the water space 9 formed between the cylinder walls and the outer wall or jacket 10 and the water jacket is provided with the water inlet and outlet connections 9' and 9" respectively. The pistons 11 reciprocate vertically in the cylinders and each is connected to its respective crank pin 12 of the crank shaft 3 by means of a connecting rod 14. Each piston is provided with a suitable packing ring 15 arranged adjacent to its upper end. This ring preferably comprises a solid or uncut ring of suitable material mounted in an annular groove 16 and held therewith by means of a screw follower 17 secured upon the upper end of the piston. The upper end 18 of the cylinder extends beyond the path of the piston to form the compression or combustion chamber 7' and within this space I mount a piston valve 21 adapted to control the flow of gases to and from the cylinder. I provide inlet and exhaust ports 19 and 20 respectively, in the cylindrical wall of the compression space 7' and I preferably make these ports circumferential, *i. e.*, I extend each of them completely around the cylinder and I arrange them parallel with each other and in planes at right angles to the axis of the cylinder. The piston valve 21 controls these ports and is reciprocated in the compression space to open and close the ports in timed relation to the movements of the piston. While the combustion chamber could be made of any suitable diameter relatively to the diameter of the cylinder, I prefer to make it of such a diameter that I can insert the valve through the lower end of the

cylinder, as this construction avoids the necessity of a separate cylinder head. As shown in the drawings, the valve and the combustion chamber are substantially of equal diameter with the cylinder. This reduces the cost of manufacture, as in this instance the compression chamber constitutes simply an extension of the cylinder and the interior cylinder surface thereof can be more cheaply finished than if a different diameter were employed. Furthermore, by making the combustion chamber the same diameter as the cylinder, I provide the longest ports possible in the form of cylinder construction illustrated, these ports being relatively so long they can be quite narrow and yet afford ample port area when open.

The piston valve 21 is in the form of a solid or uncut ring and is provided on its periphery with packing rings 22 and 23 which fit the inner cylindrical surface of the valve chamber and are adapted to close the ports 19 and 20. The ends of the valves are arranged at right angles to the axis of the cylinder and hence they are parallel with the ports. The rings are retained in position upon the body of the valve by means of an integral annular flange 24 on the lower end of the valve and a screw-threaded adjustable annular flange 24' on the upper end of the valve. The packing rings are separated longitudinally by means of a loose spacing ring 25, and when once the valve has been assembled the packing rings and the body of the valve form a substantially unitary structure. The annular flanges 24 and 24' as well as the ring 25 are of slightly less diameter than the cylinder and consequently do not contact with the cylinder. The rings which I employ are slightly compressible, that is, they can be formed by pressure and consequently when they wear so that they do not properly contact with the cylinder wall they can be set out to fit the cylinder by compressing them longitudinally by screwing the follower 24' on to the body of the valve and thus forcing to increase their outer diameter. These rings are solid, or in other words, endless, and they are made of such material that they substantially have no resiliency and as they consequently retain their form they ride over the ports without springing into them. The rings 22 and 23 are of greater width than the ports preferably about three times as wide and therefore when they are centrally over the ports they lap over at each side upon the cylinder wall and prevent the passage of gas through the ports. The spacing of the ports corresponds with the spacing of the rings and therefore when the piston is in mid-position, spanning the two ports, both ports are properly closed, and I make the spacing ring 25 as narrow as is practical in order

that the ports may be close together. It will now be seen that as the ports are relatively close together the valve can be quite short and hence it can be made light in weight.

- 5 Furthermore, the ports 19 and 20 being narrow necessitate but a short up and down movement of the valve to fully open and close the ports, and hence the work required of the valve moving mechanism is not severe.
- 10 The valve is actuated by a valve rod 26. This rod preferably extends through the cylinder head 8 concentric with the bore of the cylinder and the joint between the rod and the cylinder head is packed by a suitable stuffing box 28". The valve is provided with a central hub 27 in which the lower end of the valve rod is rigidly secured and this hub is connected with the body 28 of the valve by arms 28'. The valve rod is provided on its upper end with a connection 29 by means of which the valve can be operatively connected to the valve operating mechanism for movement up and down.

The valve and the cylinder ports as ar-

- 25 ranged provide for the opening of the exhaust port when the valve rises, and the opening of the inlet port when the valve descends. The main body or the bulk of the exhaust gases are consequently discharged 30 from the cylinder without passing through the valve and the incoming relatively cool fresh gases pass downwardly into the cylinder through the valve, and this movement of the gases out of and into the cylinder tends 35 to keep the valve at as low a temperature as possible. I make the combustion chamber 7' of sufficient length to accommodate the valve and its movement, and for the purpose of providing a combustion chamber of the 40 proper volume relative to the displacement of the piston I depress or lower the central portion of the cylinder head, as indicated at 8', and this portion of the cylinder head enters within the upper end of the valve as 45 the valve rises to open the exhaust port.

As the ports are circumferential, or, in other words, extend clear around the cylinder, the passages leading to the ports can be quite short; in fact, their length is deter-

- 50 mined by the thickness of the cylinder wall. In a single cylinder these short passages lead at once into relatively large circumferential chambers which serve, in the instance of the inlet port, to provide a relatively large body 55 of gas in the immediate vicinity of the port in position to flow into the cylinder by expansion once the port is open. This construction provides the quickest possible method of filling the cylinder with gas as 60 the gas flows into the cylinder from all sides after the manner of filling a bowl by pressing it below the surface of a body of liquid. In like manner, the large circumferential chamber connected with the exhaust port assists in the exhaust of gases

from the cylinder by the expansive action of the gases as they flow from this long port radially in all directions into the relatively large chamber, this extreme expansion of the gases actually reducing the gas within 70 the chamber to a pressure below atmosphere. This action is directly opposite to what occurs where the exhaust gases have to pass from a cylinder through a passage of contracted area such as is usually employed.

In multiple cylinder engines I dispense with walls between the corresponding circumferential chambers of the single cylinders, thereby providing a common fuel supply chamber 30 and a similar common exhaust chamber 31 connecting respectively with all of the circumferential inlet ports and exhaust ports, and both of which chambers extend longitudinally throughout the length of the engine. The large common 85 fuel supply chamber thus provided results in there being a large body of fuel gas in the immediate vicinity of and common to all of the inlet ports in position to flow into any cylinder directly the inlet port thereof 90 is opened, and consequently a rapid flow of fuel gas through the manifold which connects the carburetor with the gas chamber is more necessary. A common exhaust chamber of the kind which I employ serves 95 not only to permit instantaneous and free escape of the gases of combustion from the cylinder through the circumferential exhaust ports, but it also serves to materially 100 muffle, destroy or prevent the noise ordinarily produced by the escaping gases. This latter results from the fact that the gases, instead of being compressed as they escape from the cylinder within a relatively small exhaust pipe are permitted to expand in all 105 directions from the cylinder into the relatively large exhaust chamber and consequently they are instantly expanded to such an attenuated condition that when they finally escape from the exhaust manifold 110 they have not sufficient pressure to cause any appreciable noise; and, furthermore, the effect of this chamber, as it is in such close proximity to the ports and into which the cylinders successively discharge their contents of exhaust gases, serves as a receiver 115 or pressure equalizer and consequently the discharge from this chamber is substantially continuous instead of intermittent as results from the ordinary form of exhaust passages which are small in area.

For the purpose of reciprocating the valves to open and close the ports I provide a series of individual cams 36 mounted upon a longitudinal shaft 40 which is rotatably mounted in the base of the engine parallel with the engine shaft. This cam shaft is connected with the engine shaft by a chain 42 and sprocket wheels 43 and 44 secured respectively upon the cam shaft and the 130

engine shaft, and is rotated thereby at half the speed of the engine shaft. Each cylinder is provided with its individual valve operating mechanism which connects its valve with its respective cam and this mechanism comprises a cam rod 49' which is reciprocated vertically by its cam, a walking beam 60 mounted upon the upper end of the engine and having its inner end connected with the valve by means of the connection 29 and its outer end connected with the upper end of the reciprocating rod 49' by means of a link 51. The lower end of the cam rod 49' is provided with a cam pin 48 adapted to enter a cam groove 47 provided in the side face of the cam, and this lower end 49 of the rod is bifurcated to straddle the cam shaft which assists in retaining this end of the rod laterally in place while permitting the rod to be vertically reciprocated. This cam rod is mounted in the vertical guide 50 which is secured upon the upper face of the lower casting B. The inner end 60' of the walking beam is longer than the outer end and the two ends are so proportioned that the relatively small movement provided by the cam groove is increased sufficiently to move the valve its proper distance. The connection of the inner end 60' of the walking beam with the upper end of the valve rod is such that the valve rod can move freely up and down through the stuffing box 28" without lateral pressure due to the swinging movement of the walking beam. The connection 29 comprises two spaced collars 29' and the end 60' of the walking beam is bifurcated and the termination 60" of each part is in cylindrical form of a diameter to fit between the two collars 29'. The cams are what may be termed face cams, that is, each cam groove 47 is arranged in one of the side faces of the cam and in order to keep the lower end 49 of the cam rod properly positioned in relation to the face of the cam I provide a washer plate 40' rigidly secured upon the shaft between which and the face of the cam the lower end of the cam rod is free to reciprocate. The cam shaft with its cams is mounted in the upper portion of the base of the engine, and in order to properly lubricate the cams I inclose the cams in a casing by means of an interior partition wall 65, and I provide an oil pump in the lower part of the engine base driven from the cam shaft through a pair of screw gears 57. This pump draws oil from the oil base 68 of the engine and delivers it into the casing 65. The height of the oil in this cam casing is determined by an overflow pipe 69 through which the surplus oil returns to the base of the engine. The valves of the various cylinders in the multiple cylinder engine are caused to move in their proper time relation relative to the

movement of their respective pistons by adjusting the individual cams to their proper relative angular position upon the cam shaft.

In Figs. 1 and 4 I show the three principal positions of the valve. At 62 I have shown the inlet port open, at 63 I have shown the exhaust port open, and at 64 I have shown the valve in mid-position in which position both ports are closed. As the engine illustrated is what is known as a four-cycle engine, the valve remains in its mid-position during the compression and explosion strokes of the piston, or, in other words, during one complete revolution of the engine shaft and it then moves upwardly to open the exhaust port, this movement occupying substantially one half of the next revolution of the shaft. At the end of the exhaust period the valve moves downwardly to open the inlet port and then back to its mid-position, this movement to open and close the inlet port occupying substantially the next half revolution of the crank shaft. It will now be apparent that the only movement of the valve at times when there is pressure in the cylinders occurs when it opens the exhaust port, but as the valve is a complete ring, and is therefore in a practical sense inexpandible, even at this time it does not contact with the cylinder wall with any greater pressure than at any other times and consequently it does not require any great amount of power to operate the valve.

One important advantage arising from the long circumferential ports and the relatively large fuel gas chamber in immediate connection therewith is that the movement of the valve to open the inlet port can be delayed. In other words, the slot of the cam which provides this movement of the valve can be much more gradual than in the usual construction. The result of this being that the valve is not only easily moved but the valve mechanism is very quiet, almost silent in its operation, at least compared with the usual puppet valve construction. A further advantage which accrues from this construction is that I provide an engine which can be throttled down to a very low speed and yet have a powerful torque, for the reason that as the cylinders always receive their full quota of fuel gas unadulterated by free air, the explosions are not interrupted as frequently occurs when an ordinary puppet valve engine is throttled to a very low speed.

As many modifications of my invention will readily suggest themselves to one skilled in the art, I do not confine or limit my invention to the specific structure herein shown and described.

I claim:

1. In an internal combustion engine a power cylinder, in combination with a piston

arranged to reciprocate therein, two endless circumferential substantially parallel ports in the wall of the cylinder beyond the path of the movement of the piston, a sleeve valve within the cylinder of a length to close both of said ports at the same time, and means for reciprocating said valve in timed relation with the movement of the piston for opening and closing said ports.

2. In an internal combustion engine having a crank shaft, a power cylinder arranged above the crank shaft, in combination with a reciprocating piston therein and a connecting rod connecting the piston with the shaft, a combustion chamber arranged within the cylinder above the upper position of the piston, said chamber being substantially concentric with the cylinder, two substantially parallel circumferential ports in the wall of the combustion chamber, each thereof extending completely around the cylinder, a sleeve valve within the combustion chamber adapted to close both of said ports at the same time, and valve operating mechanism connecting the valve with the crank shaft for reciprocating the valve to open and close said ports in timed relation with the movements of the piston.

3. In an internal combustion engine the combination with a crank shaft, a cylinder arranged substantially vertically above the shaft, a power piston within the cylinder and a connecting rod operatively connecting the piston with the crank shaft, said cylinder extending above the upper position of the piston and being closed at its upper end to form a combustion chamber and being of substantially uniform diameter throughout its length, two substantially endless parallel circumferential ports in the wall of the cylinder lying in planes at right angles to the axis of the cylinder and above the path of the piston, a sleeve valve reciprocatively mounted within the upper end of the cylinder adapted to close both of said ports at the same time and having its ends arranged parallel with the ports, and mechanism connecting the valve with the crank shaft for moving the valve up and down in the cylinder to open and close said ports in timed relation with the movements of the piston.

4. In an internal combustion engine the combination with a power cylinder and piston arranged to reciprocate therein, of a circumferential fuel inlet port extending completely around the cylinder near the upper end thereof, a similar exhaust port arranged in the wall of the cylinder substantially parallel with and spaced below said inlet port, a reciprocating sleeve valve within the cylinder of a length to span said ports and to cover or close them both at the same time, and means for reciprocating said valve in timed relation with the movements of the piston for opening and closing said ports.

5. In an internal combustion engine a power cylinder and a piston reciprocating therein, a head closing the upper end of the cylinder to form a combustion chamber, inlet and exhaust ports in the wall of the combustion chamber arranged circumferentially and spaced apart and lying in planes at right angles with the axis of the cylinder, each thereof extending completely around the cylinder, a piston valve within said combustion chamber, endless packing rings in said valve for controlling said ports, a valve rod centrally mounted on said valve and projecting centrally through the head, and mechanism operatively connecting the outer end of the valve rod with the piston for reciprocating the valve in timed relation thereto.

6. In an internal combustion engine the combination with a cylinder and a power piston reciprocating therein, of two endless circumferential ports in the cylindrical wall of the cylinder above the upper position of the piston, a sleeve valve arranged in the upper end of said cylinder, two endless parallel circumferential packing rings on the outer part of the valve, said rings being spaced apart substantially coincident with the spacing of said ports and adapted when the valve is in mid-position to close both of said ports, and mechanism operatively connecting said valve with the engine shaft for moving said valve up and down in the cylinder to open and close said ports in timed relation to the movements of said piston.

7. In an internal combustion engine a cylinder and a reciprocating power piston therein, in combination with a sleeve valve mounted in the upper end of the cylinder and adapted to be reciprocated up and down therein, said valve being in the form of a ring having its middle portion open for the passage of gas, a circumferential inlet port arranged in the cylindrical wall of the cylinder, a similar circumferential exhaust port also arranged in the wall of the cylinder parallel with and spaced below said inlet port, said piston valve being adapted to close both of said ports at the same time to open the inlet port when moved downwardly in the cylinder and to open the exhaust when moved upwardly in the cylinder from its mid-position, said valve having a central hub connected to the ring portion by a number of their arms, a piston rod rigidly connected to the hub of the valve and extending through the cylinder head, and mechanism operatively connecting said piston rod with the engine shaft for reciprocating said valve in timed relation with the reciprocations of the power piston.

8. In an internal combustion engine a power cylinder and a piston reciprocating therein, the cylinder being extended beyond the path of the piston and closed at its

70

upper end to form a compression space, endless circumferential ports in the walls of the cylinder for the inlet and exhaust of the gases, a valve in the form of a ring open at 5 its middle portion for the passage of gases, the cylinder head being formed to project within said open middle space when the piston valve is at the upper limit of its movement, said valve having a central hub connected to the valve by several thin vertically extending arms, a piston rod secured in said hub and projecting through the cylinder head, and mechanism connecting the outer end of said rod with the engine shaft for 10 reciprocating said valve in timed relation 15 with the reciprocations of the piston.

9. In a multiple cylinder internal combustion engine, a plurality of power cylinders arranged parallel with each other, a reciprocating piston in each said cylinder, an 20 endless circumferential inlet port in the cylindrical wall of each cylinder adjacent to its upper end, said engine being provided with a continuous fuel gas supply chamber 25 completely encircling each of said cylinders and in free communication with the whole extent of each of said inlet ports, a similar endless circumferential exhaust port in each said cylinder arranged parallel with and 30 spaced from said inlet port, said engine being provided with an exhaust chamber completely encircling each of said cylinders and in free communication with the whole extent of each of said exhaust ports and a 35 reciprocating piston valve for each cylinder for controlling the ports thereof.

10. In a multiple cylinder engine having a plurality of parallel power cylinders, a fuel gas supply chamber common to and 40 surrounding all of said cylinders and an exhaust chamber arranged below said fuel supply chamber and common to and surrounding all of said cylinders, each of said cylinders having a circumferential port in 45 its upper end opening directly into said fuel supply chamber around the whole circumference of the cylinder, a similar circumferential exhaust port parallel with and spaced below said inlet port and opening 50 directly into said exhaust chamber around the whole circumference of the cylinder and a piston valve within each cylinder for controlling the ports thereof.

11. In an internal combustion engine a power cylinder, in combination with a piston arranged to reciprocate therein, two circumferential ports in the wall of the cylinder beyond the path of the movement of the piston, the wall of the cylinder being 55 completely secured by each said port; a sleeve valve within the cylinder of a length to close both of said ports at the same time, and means for reciprocating said valve, in timed relation with the movements of the 60 piston, for opening and closing said ports.

12. In an internal combustion engine a power cylinder, in combination with a piston arranged to reciprocate therein, two ports in the wall of the cylinder extending entirely around the cylinder and arranged 70 one above the other beyond the path of the movement of the piston, a sleeve valve within the cylinder of a length to close both of said ports at the same time, and means for reciprocating said valve, in time with the 75 movements of the piston, for alternately opening and closing said ports.

13. In an internal combustion engine a power cylinder, in combination with a piston arranged to reciprocate therein, two substantially parallel ports in the wall of the cylinder one above the other beyond the path of the movement of the piston and each thereof extending a complete circumference, a sleeve valve within the cylinder of 80 a length to close both of said ports at the same time, and means operatively connecting the valve and piston for reciprocating said valve, in time with the movements of the piston, for opening and closing said 85 ports.

14. In an internal combustion engine the combination with a cylinder and a power piston reciprocating therein, of two ports in the cylindrical wall of the cylinder above 90 the upper position of the piston, each of said ports being longitudinally equal to the circumference of the cylinder, a cylindrical valve member within the cylinder the periphery of which closes said ports and means 95 for reciprocating the valve to open and close the ports alternately.

15. In an internal combustion engine the combination with a cylinder and a power piston reciprocating therein, of two endless 100 circumferential ports in the cylindrical wall of the cylinder above the upper position of the piston, a cylindrical valve member within the cylinder for controlling said ports, and packing disposed in the periphery of 105 the valve member serving to close both ports when the valve is in midposition, and means for moving said valve in time with the reciprocations of the piston, to 110 open and close said ports.

16. In an internal combustion engine, the combination with a cylinder and a power piston reciprocating therein, of two endless circumferential ports in the cylindrical wall of the cylinder above the upper position of the piston, a cylindrical valve member within the cylinder for controlling said ports and solid packing rings disposed in the periphery of the valve member for producing a pressure tight joint between the piston and the cylinder and means for moving said valve in time with the reciprocations of the piston to open and close said ports.

17. In an internal combustion engine, the 115

combination with a cylinder and a power piston reciprocating therein, of two endless circumferential parallel ports in the cylindrical wall of the cylinder beyond the path 5 of the piston, a ring-like valve member movable within the cylinder for controlling said ports and endless adjustable packing rings disposed in the periphery of the valve member and serving to close both ports when 10 the valve is in midposition, and means for moving said valve in time with reciprocations of the piston, to open and close said ports.

18. In an internal combustion engine, a 15 power cylinder, in combination with a piston arranged to reciprocate therein, two substantially parallel ports in the wall of the cylinder, one above the other beyond the path of the piston and each thereof extending completely around the cylinder, a ring valve within the cylinder for controlling said ports, endless pliable metallic packing rings in the periphery of the ring valve adapted to open and close said ports 20 and means carried by the valve whereby said rings can be expanded in diameter.

19. In an internal combustion engine, a 25

power cylinder, in combination with a piston movable therein, two substantially parallel ports in the wall of the cylinder, each 30 thereof extending completely around the cylinder, a sleeve valve within the cylinder for controlling said ports, the valve having a circumferential groove in its periphery, a malleable endless metallic ring completely 35 filling the groove, and in contact with the wall of the cylinder, and a packing compressing ring carried by the valve.

20. In a multiple cylinder engine, a plurality of cylinders each thereof having a 40 port in its cylindrical wall which is endless and extends a complete circumference, in combination with a continuous chamber surrounding each of said cylinders and having free communication with the whole of each 45 of said ports.

In testimony whereof, I have hereunto set my hand, this 14th day of December, 1911, in the presence of two subscribing witnesses.

RALPH H. ROSENBERG.
